Des. 227,168
Patented June 5, 1973

227,168

SUMP PUMP

David O. Chase and Martin V. Maloney, Skaneateles,
N.Y., assignors to Houdaille Industries, Inc., Buffalo,
N.Y.

Filed Apr. 6, 1972, Ser. No. 241,878

Term of patent 14 years

Int. Cl. D15—02

U.S. Cl. D65—1 R

Fig. 1

Fig. 2

Fig. 3

FIG. 5

FIG. 4

FIG. 6

FIG. 1 is a front elevational view of a sump pump showing our new design.

FIG. 2 is an elevational view taken from one side thereof.

FIG. 3 is an elevational view taken from the side opposite that shown in FIG. 2.

FIG. 4 is a rear elevational view thereof.

FIG. 5 is a top plan view thereof.

FIG. 6 is a bottom plan view thereof.

We claim:

The ornamental design for a sump pump, substantially as shown.
